UNITED STATES PATENT OFFICE.

T. CLARENCE HEISEY, OF NEWARK, OHIO, ASSIGNOR TO A. H. HEISEY & COMPANY, OF NEWARK, OHIO.

DESIGN FOR A DISH.

Application filed March 20, 1923. Serial No. 5,546. Term of patent 14 years.

To all whom it may concern:

Be it known that I, T. CLARENCE HEISEY, a citizen of the United States, residing at Newark, in the county of Licking and State of Ohio, have invented a new, original, and ornamental Design for a Dish, of which the following is a specification, reference being had to the accompanying drawings, forming part thereof.

I claim:—

The ornamental design for a dish, as shown.

T. CLARENCE HEISEY.
